UNITED STATES PATENT OFFICE.

CARL E. RETT, OF AKRON, OHIO.

VULCANIZING PRESS.

Application filed May 3, 1922. Serial No. 558,098.

To all whom it may concern:

Be it known that I, CARL E. RETT, a citizen of the United States, residing at Akron, in the county of Summit and State of Ohio, **5** have invented certain new and useful Improvements in Vulcanizing Presses, of which the following is a specification.

This invention relates to vulcanizing presses particularly adapted and intended **10** for the vulcanization of pneumatic tires in molds, but capable of course of use for vulcanizing any articles to which it may be suitable.

In vulcanizing tires for example, it is common **15** to enclose the tire molds in a rather long or high upright tank or chamber below which is a hydraulic plunger or ram having a stem or piston rod which works in a well. This makes a high and costly structure, frequently **20** extending through several floors of a factory, and is attended with various other objections some of which will be referred to hereinafter.

One of the objects of the present invention **25** is to provide a construction which avoids or omits the use of the long well or pressure chamber for the rod of the hydraulic press. By this means the height of the structure is materially lessened.

30 A further object of the invention is to provide a construction in which the pressure chamber is made of sections so that this height may be varied according to the capacity desired.

35 A further object of the invention is to improve the means for collecting and removing the condensate resulting from the steam used in the pressure chamber. This is done by means of an annular collecting chamber, **40** near the bottom of the press, surrounding a barrel or cylinder which forms a continuation of the upper part of the tank and in which the plunger is caused to move by hydraulic pressure admitted below.

45 A further object of the invention is to provide improved means for making the steam and water connections for the supply and removal thereof in consequence of the heating and cooling operations.

50 Various other details of improvement will be apparent from the following description and the accompanying drawings in which Figure 1 is a side elevation of the press. Fig. 2 is a central vertical section. Fig. 3 is **55** a section on the line 3-3 of Fig. 2. Fig. 4

is a side elevation of the hydraulic ram or plunger.

The pressure tank or chamber consists of a series of sections 6 connected by bolted flange joints 7, and the number of these sections **60** may be varied according to the capacity desired. At the top is a section 8 which has a removable cover 9 which may be held in place by the ordinary castellated lock 10, but which can be removed when the molds are to **65** be discharged from the heating chamber. This upper section 8 is also provided with flood water outlets 11, which will be connected to suitable valved pipes leading to waste or otherwise. These outlets are located in high position, quite close to the top of the pressure chamber, so that all the molds in the chamber can be flooded during the cooling operation. The cover 9 is hollow, as shown at 12, with an insulating plate 13 **70** thereunder, so that loss of heat is prevented, a gasket 14 being placed at the joint for the plate to seat against.

Near the lower end of the pressure chamber is a section 15, the side wall of which is **75** somewhat flared at the bottom as indicated at 16 and provided with a set of spaced ribs 17 with grooves between, and these grooves communicate with an annular chamber 18 in the section 19 next below. The inner faces **80** of the ribs 17 are flush with the inner surface of the main body of the pressure chamber, and also flush with an inner cylinder or barrel 20 which is supported or mounted within the lower part of the structure, by means **85** of an external flange 21 which is bolted between the lower flange of the section 19 and a flange at the upper edge of a cupped base member 22, which may be supported on a concrete block or otherwise to carry the **90** weight of the whole apparatus. The flange 21 also forms a partition between the condensate chamber 18, and the water pressure chamber 23 in the base member 22, and the barrel 20 extends upwardly into the section **95** 19 and downwardly in the section 22, being spaced from the bottom of the latter as indicated at 24 to allow the water to enter below the hydraulic ram or plunger which works in the barrel 20 and is also capable of **100** being moved upwardly throughout practically the whole length of the pressure chamber. The plunger consists of an upper member 25 which has radial ribs 26 spaced apart to form outlets through which the water of **105** 110

condensation can drain into the collecting chamber 18. This head member 25 is mounted upon an intermediate section 26 and this in turn is mounted on a lower member 28 and a bottom ring member 29, these members having supporting webs 30 and 31 to stand the strain. The several members of which the plunger is built up are rebated at the joints to receive the packing rings 32. This sectional construction is advantageous, and being hollow serves to insulate the pressure chamber from the water chamber below. The sections can also be handled and fitted easier than a solid plunger.

15 The section 15 is provided with a steam connection 33 for the inlet of steam to the pressure chamber. The condensation section 19 is also provided with a connection 34 for removal of the water of condensation and for the admission of the cooling or flooding water. The base section 22 has a connection 35 for the water pressure. All of these connections will be provided with suitable valves in the pipes leading thereto, to control the various operations.

20 As usual, the tires to be vulcanized are enclosed in molds 40, which are stacked in through the top, the bottom mold resting on the ribs 26 on the plunger head.

25 In operation, the pressure chamber being filled with molds, the hydraulic plunger is lifted by water admitted through the connection 35 to the chamber 23, and pressing upwardly on the plunger lifts the same to press the molds. Steam is then admitted through the connection 33 into the pressure chamber, and the molds are heated to effect the vulcanization. The water of condensation flows down into the annular well 18 and may be let out to waste. The steam being turned off, the molds are then cooled by admitting water through the connection 34, and this water rises from the condensation chamber into the heating chamber until it is let out through the outlets 11. The cover 9 being then removed, the hydraulic plunger is lifted to raise the stack of molds out through the top of the tank, and the operation may then be repeated with the next stack of molds. The controlling valves for the various supply and waste connections will of course be manipulated according to the progress of the operations.

30 I claim:

55 1. A vulcanizing press comprising an upright chamber provided at its lower end with an internal barrel, a condensate chamber surrounding said barrel, and a hydraulic plunger working in said barrel.

60 2. A vulcanizing press comprising an upright chamber provided at its lower end with an internal barrel, the wall of the chamber being spaced around the barrel to form an annular condensate chamber, and a hydraulic plunger working in said barrel.

3. A vulcanizing press comprising an upright chamber formed in sections, a barrel supported within the lower sections, said lower sections being enlarged and spaced from the barrel to form an annular condensate chamber surrounding the barrel, and a hydraulic plunger working in the barrel.

4. A vulcanizing press comprising an upright chamber, an internal barrel supported in the lower end of said chamber, an annular condensate chamber surrounding said barrel and communicating at its upper end with the chamber above the barrel, said barrel being open at its lower end, a plunger working in the barrel, and a closed base member supporting said chambers and forming a hydraulic pressure chamber open to the lower end of the barrel.

5. A vulcanizing press comprising an upright pressure chamber, an annular condensate chamber at the lower end of said pressure chamber and communicating therewith, a barrel supported within the condensate chamber in line with the pressure chamber, and a hydraulic plunger working in the barrel and pressure chamber.

6. A vulcanizing press comprising an upright pressure chamber, an annular condensate chamber thereunder, and a water pressure chamber under the condensate chamber and forming the base of the machine, a barrel supported in the condensate and hydraulic pressure chambers, said barrel being open at its top to the pressure chamber and at its bottom to the water chamber, and a plunger working in the barrel and the pressure chamber.

7. A vulcanizing press comprising an upright tubular pressure chamber adapted to receive molds, a tubular section under said upright chamber, and a cupped base section under the last mentioned section, a barrel supported in the two lower sections and spaced from the side walls thereof to form a condensate chamber and a water pressure chamber, a partition between the last mentioned chambers, said partition extending from the barrel to the outer wall of said chambers, and a hydraulic plunger working in the barrel and the pressure chamber, the inner surfaces of the barrel and the pressure chamber being flush with each other to permit the travel of the plunger.

8. A vulcanizing press comprising an upright pressure chamber, and a hydraulic plunger at the bottom of said chamber, said plunger consisting of hollow sections.

9. A vulcanizing press comprising an upright pressure chamber, and a hydraulic plunger at the bottom of said chamber, said plunger consisting of hollow sections, and provided with packing rings at the joints between the sections.

10. A vulcanizing press comprising an up-

right chamber having at its lower end an annular condensate chamber communicating at its upper end with said pressure chamber, a barrel within and spaced from the wall of the condensate chamber, and a hydraulic plunger working in the barrel, said plunger having spaced ribs at its top.

11. A vulcanizing press comprising an upright chamber having an enlarged section 10 at its lower end, a barrel supported in said enlarged section and spaced therefrom to form a condensate chamber, the walls of said barrel being in line with the walls of the pressure chamber, and the upper end of 15 the condensate chamber being provided with spaced ribs to permit the escape of condensate from the pressure chamber to the condensate chamber, and a hydraulic plunger working in the barrel and pressure chamber.

12. A vulcanizing press comprising an upright pressure chamber with an enlarged section at its lower end, a cup-shaped base member under said lower section and form-

ing a water pressure chamber, and a barrel 25 supported in the enlarged section and the base chamber, said barrel having an external flange forming a partition between the water pressure chamber and the space above the same, and a hydraulic plunger working 30 in the barrel and pressure chamber.

13. A vulcanizing press comprising an upright pressure chamber having water outlets near the top and a condensate chamber at the bottom, said condensate chamber being 35 provided with a water connection, and the pressure chamber being provided with a connection for steam, a barrel supported in the condensate chamber, in line with the pressure chamber, and a hydraulic plunger 40 working in the barrel and the pressure chamber.

In testimony whereof, I affix my signature in presence of two witnesses.

CARL E. RETT.
